US0D1105968S

(12) **United States Design Patent** (10) **Patent No.:** **US D1,105,968 S**
(45) **Date of Patent:** **** Dec. 16, 2025**

(54) **PAIR OF EARRINGS**

(71) Applicant: **Harry Winston SA**, Plan-les-Ouates (CH)

(72) Inventor: **Delphine Abdourahim**, New York, NY (US)

(73) Assignee: **Harry Winston SA**, Plan-les-Ouates (CH)

(**) Term: **15 Years**

(21) Appl. No.: **29/970,924**

(22) Filed: **Oct. 31, 2024**

(30) **Foreign Application Priority Data**

May 10, 2024 (WO) WIPO148272

(51) **LOC (15) Cl.** **11-01**

(52) **U.S. Cl.**

USPC **D11/43**
